UNITED STATES PATENT OFFICE.

ESEK BUSSEY, OF TROY, NEW YORK, ASSIGNOR OF ONE-HALF OF HIS RIGHT TO CHARLES A. McLEOD, OF SAME PLACE.

DESIGN FOR HEATING-STOVES.

Specification forming part of Design No. 11,525, dated November 25, 1879; application filed June 25, 1879.
[Term of patent 7 years.]

To all whom it may concern:

Be it known that I, ESEK BUSSEY, of the city of Troy, county of Rensselaer, and State of New York, have invented a new Design for Heating-Stoves, of which the following is a specification.

My invention of a design for heating-stoves consists in combining with the rectangular ash-pit section of a heating-stove, for ornamental effect, two foot-rails, one of them being placed at the top, or near the top, and the other at the bottom, or near the bottom, of the ash-pit section of the stove.

In the accompanying illustration, which forms a part of this specification, there is shown a heating-stove having the base B, rectangular ash-pit section C, upper foot-rail, A, and lower foot-rail, D.

The two foot-rails and the ash-pit section of the stove may have the surface ornamentation shown; or other ornamentation may be employed, and the same general effect will be produced by the combined elements constituting my invention.

I am well aware that one foot-rail has been employed to ornament a stove-base; but the location of an additional one above the other, and in combination with it, produces an entirely different impression upon the eye from that made to appear where a single rail was thus used.

Having thus described my invention of a design, what I claim, and desire to secure by Letters Patent, is—

The design for the ornamentation of the ash-pit section of a heating-stove, consisting of the upper and lower foot-rail and intermediate rectangular form of the ash-pit section, as shown and described.

Signed at Troy, New York, this 23d day of June, 1879.

ESEK BUSSEY.
